UNITED STATES PATENT OFFICE.

ABRAHAM A. SHOBE AND WILLIAM EMBLEY, OF JERSEYVILLE, ILLINOIS.

GRIPPER FOR CABLE RAILWAYS.

SPECIFICATION forming part of Letters Patent No. 379,993, dated March 27, 1888.

(Application filed April 23, 1887. Serial No. 235,841. No model.)

To all whom it may concern:

Be it known that we, ABRAHAM A. SHOBE and WILLIAM EMBLEY, of Jerseyville, in the county of Jersey and State of Illinois, have invented a new and Improved Gripper for Cable Railways; and we do hereby declare that the following is a full and exact description of the same, reference being had to the accompanying drawings, and to the letters of reference *IC* marked thereon.

Our invention relates to an improvement in grippers for cable railways; and it consists in providing new and improved mechanism for lifting the cable, however great the slack may be, and consequent deflection between the supporting carrier-wheels, to a position within reach of the clamping-jaws, so that the cable may be readily cast off and taken up as required.

With this end in view our invention consists, essentially, in combining with the movable gripping-jaws and the mechanism by which the latter are actuated an auxiliary arm, the office of which is to lift the cable and conduct it into the channel of the lower gripping-jaw.

In the drawings, Figure 1 is a side elevation of the gripper, showing the hand-lever mechanism by which it is operated. Fig. 2 is a vertical transverse section of the same, taken in the line *x x*, Fig. 1, the hand-lever being omitted; and Fig. 3 is a back view, upon an enlarged scale, of the lower part of what is shown in Fig. 1.

In the drawings, *A* represents a part of the frame of the bottom of the car, to which are secured by angle-irons *a*, as shown, vertically depending bars *B*, connected together by the angle-irons *a* and the fixed grip-jaw *b*. Adapted to slide vertically between the bars *B*, and actuated by a link and latch-lever, as shown, is a bar, *C*, connected by a link, *c*, Fig. 2, with a pair of movable grip-jaws, *d*, which are secured upon an arbor, *e*, the latter journaled in bearings in each end of the fixed jaw. Journaled upon the central part of the arbor *e*, and adapted to vibrate freely thereon, is a curved

auxiliary lifting arm *f*, of such length as to reach below the lowest point ever attained by the slack of the cable between the carrier-wheels. At the back of said auxiliary arm is 50 a bar, *g*, each end of which is secured in one of the movable jaws, and against which the back of the auxiliary arm rests, as shown in Fig. 3.

The several parts of our device being constructed and combined as above described, and 55 shown in the drawings, its operation is as follows: When it is desired to pick up and clamp the cable, the latch-lever is moved as indicated by the arrow. This thrusts the bar *C* downward, and consequently the grip-jaw *d* upward, 60 and with it the lifting-arm *f*, as indicated by the arrow. As the lifting-arm approaches the horizontal position, the cable is conducted into the channel *h* of the movable jaw *d*, by which it is further lifted to the channel in the fixed 65 jaw *b*, and there firmly clamped for the propulsion of the car.

It is obvious that this device may be applied to either side of the bars *B*, or to both sides, if so required, by the simple duplication of the 70 parts shown, one auxiliary arm remaining in a pendulous position while the other is in operation.

Having fully described our invention, what we claim, and desire to secure by Letters Patent, is—

In a gripping device for cable railways, the combination, with a pair of movable grip-jaws adapted to vibrate upon an arbor, of an auxiliary arm or cable-lifter actuated by a bar 80 located at the back thereof, each end of which is secured in one of the movable jaws, all constructed and adapted to operate substantially as and for the purpose set forth.

In testimony that we claim the foregoing we 85 have hereunto set our hands this 11th day of April, 1887.

ABRAHAM A. SHOBE.
WILLIAM EMBLEY.

Witnesses:

J. W. McEVERS,
R. L. VAN DENBURG.
